CLOTHING MANUFACTURE ACCESSORY

BACKGROUND OF THE INVENTION

This invention relates to a prefabricated loop for use in particularly, but not exclusively, the manufacture of clothing.

In the manufacture of dresses and skirts the requirement arises for loops of various sizes and various purposes, e.g. belt loops, loops for retaining a dress on a hanger in transit, loops for retaining a skirt on a hanger. In general, these loops have been made of dress material in the first case and of suitable lengths of tape in the second and third cases, e.g. 9-inch loops and 3½-inch loops which require sewing into the garments.

SUMMARY OF THE INVENTION

The present invention consists in a prefabricated loop for use in making dresses and the like, comprising a length of tape or the like, and a length of fine thread of extruded plastic monofilament or the like, looped and with its ends secured to the tape.

A plurality of such loops may be provided along the length of the tape on one or both sides formed from a single length of thread, monofilament or the like or from separate lengths.

To obtain separate prefabricated loop structures the tape may be cut transversely (and, in the case of loops on both sides, also longitudinally).

In use the prefabricated loops are placed in position so that the normal stitching operation secures the tape with the loop projecting where it is required.

The invention will be further described with reference to an embodiment shown by way of example in the accompanying drawing, wherein:

BRIEF DESCRIPTION OF THE DRAWINGS

FIG. 1 is an enlarged view of part of a tape having a plurality of loops, and

FIG. 2 shows part of a garment having two prefabricated loops hung on a hanger.

DETAILED DESCRIPTION OF THE INVENTION

In FIG. 1, a length of tape 1 is formed from a plurality of warp threads 2 and a continuous weft monofilament 3 of e.g. nylon or terylene. As can be seen from FIG. 1 a loop 4 is formed by drawing the weft 3 laterally out of the side of the tape 1 during the weaving of the tape. The loops 4 may be drawn out of one side or both sides of the tape 1.

Preferably, the extruded monofilament is of a transparent or translucent nature so that it takes up the color of the dress or the like material and is substantially invisible in use.

In use, the tape is cut along the lines A-A of FIG. 1 and the piece of tape 1a having a loop 4 is sewn inside a garment. In

FIG. 2, two such pieces of tape have been sewn into the shoulders 5 of a dress 6. The loops 4 are normally hidden inside the shoulders of the dress when it is being worn. When the dress is hung on a clothes hanger 7, the loops 4 are slipped over the hanger hook 8 and thus prevent the shoulders 5 sliding off the hanger 4.

In order to form a belt loop, the piece of tape 1a is sewn inside the seam of the garment, e.g. a dress, or trousers, so that the tape is held in the seam and the loops hang on the outside 10 of the garment. Alternatively, the loop 4 is pulled through the garment by means of a needle or hook so that the monofilament-thread loop projects from the garment and is retained to the garment by the tape.

In order to form a "hanging-up loop," the piece of tape 1a is 15 sewn inside the top of the back, or in the collar of the garment.

Various other methods of manufacturing prefabricated loops are possible.

Thus, in one further method an extruded plastic monofilament of, say, nylon, is zigzagged across a tape, which may also be of nylon, to form two parallel rows of loops in staggered relation. A second tape, which may also be of nylon, is placed along the first-mentioned tape across the zigzagged monofilament and is heat sealed or welded thereto by some form of heating means. The welded tapes may be then cut longitudinally by a heat or mechanical cutting operation to provide a series of loops which may be separated as desired.

Alternatively, the individual ends of the thread or monofilament may be secured to the tape by sewing.

The thread or monofilament could also be lock- or chain-stitched along the longitude of the tape with spaced loops drawn out at the side.

The loops may also be made in the fiber or monofilament by means of a "knotting" operation to produce a series of loops or to manufacture the single loops (similar in shape to an elastic band) which may be incorporated into the article at the position required either by stitching or welding or the such like.

The use of the prefabricated loops need not be confined to clothing. For example, the prefabricated loops could be used 35 for hanging curtains.

I claim:

1. In a garment body covering provided with an opening, at least two tape segments, each segment having a loop, means 45 securing each tape segment to the inner face of the garment material adjacent the opening, with the tape segments being approximately diametrically opposed across the opening, and the loops being of such length as to contact one another in the center of the opening whereby the loops may be placed over the hook element of a garment hanger to prevent the garment sliding off the hanger.

2. The garment as claimed in claim 1 in which each tape segment includes a length of woven material and said loop constitutes the weft of the tape segment.
